CLAIM

The ornamental design for a cutting tool, as shown and described.

DESCRIPTION

FIG. 1 is a front view of a cutting tool of a first embodiment showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is an enlarged view of the portion 9 in FIG. 1;

FIG. 10 is an enlarged view of the portion 10 in FIG. 7;

FIG. 11 is an enlarged view of the portion 11 in FIG. 8;

FIG. 12 is a cross sectional view taken along line 12-12 in FIG. 1;

FIG. 13 is a cross sectional view taken along line 13-13 in FIG. 9;

FIG. 14 is a cross sectional view taken along line 14-14 in FIG. 9;

FIG. 15 is a cross sectional view taken along line 15-15 in FIG. 9;

FIG. 16 is a cross sectional view taken along line 16-16 in FIG. 9;

FIG. 17 is an enlarged view of the portion 17 in FIG. 12;

FIG. 18 is an enlarged view of the portion 18 in FIG. 13;

FIG. 19 is an enlarged view of the portion 19 in FIG. 14;

FIG. 20 is an enlarged view of the portion 20 in FIG. 15; and,

FIG. 21 is an enlarged view of the portion 21 in FIG. 16.

(Continued)

The dash-dash broken lines in the drawings illustrate portions of the cutting tool that form no part of the claimed design. The dash dot-dash broken lines are used to show a border and form no part of the claimed design.
